Patented May 15, 1917.

Fig. 1.

UNITED STATES PATENT OFFICE.

OTTO KARCHER, OF CANTON, OHIO.

DISPENSING DEVICE.

1,226,218.

Specification of Letters Patent. Patented May 15, 1917.

Application filed February 3, 1915. Serial No. 5,811.

To all whom it may concern:

Be it known that I, OTTO KARCHER, a citizen of the United States, residing at Canton, in the county of Stark and State of Ohio, have invented a new and useful Dispensing Device, of which the following is a specification.

My invention relates to dispensing devices and consists of a receptacle designed 10 to hold a quantity of oyster crackers, lump sugar, salted peanuts or other food stuff of suitable size and shape to be dispensed in this manner, the articles contained therein adapted to be removed in small quantities 15 when desired.

The present invention relates more particularly to a device of this character in which the crackers or other articles contained therein will at all times be kept under cover so that they will remain fresh and in a sanitary condition, and the device is more especially adapted to be used in dining rooms, restaurants or public eating places in general, it being impossible for the 20 user to handle any of the articles contained in the device, except those which he dispenses therefrom for his own use.

The object of the present invention is to provide a dispensing device in which the 30 articles to be dispensed are kept in a sanitary state and may be dispensed in small quantities from time to time.

Another object is to provide such a device in which it will be impossible in operating the device to handle any of the articles contained therein, except those withdrawn for his own use by the operator.

Another object is to provide a dispensing device of the character referred to which 40 will be inexpensive to manufacture and easy to operate.

Another object is to provide a dispensing device of the character referred to which is designed not to break or crumb the crackers or other articles to be dispensed therefrom.

With these objects in view the invention consists in the novel construction and arrangement of parts, hereinafter described, 50 illustrated in the accompanying drawings, and particularly pointed out in the appended claims, it being understood that various

changes in the form, proportion, size and minor details of construction may be made within the scope of the appended claims 55 without departing from the spirit or sacrificing any of the advantages of the invention.

In the accompanying drawings:

Figure 1 is a vertical sectional view of my improved dispensing device. 60

Fig. 2 is a detail perspective view of the inverted dispensing cup.

Fig. 3 is a side elevation of the same.

Fig. 4 is a fragmentary sectional view upon an enlarged scale, showing the hinged 65 covers upon the dispensing cup.

Fig. 5 is a section on line 5-5, Fig. 3.

Fig. 6 is a detail perspective view of one of the hinged covers.

Similar numerals of reference indicate 70 corresponding parts throughout the several figures of the drawing.

The containing receptacle 1 and cover 2 are preferably formed of glass, although they may be made of any other suitable material. The cover 2 is preferably provided with a downwardly disposed annular flange 2^a adapted to fit within the containing receptacle at the upper edge thereof for the purpose of retaining the cover upon the containing receptacle. The reduced lower portion 3 of the containing receptacle is adapted to fit snugly within a ring 4 carried upon a supporting leg 5, said leg having a foot 6 which is attached to a suitable base 7, the 80 ring, leg and base being preferably formed of metal. 85

The interior of the containing receptacle is inclined as shown at 8 toward the restricted cylindrical neck 9 and slidably 90 mounted within the neck is an inverted dispensing cup 10, said dispensing cup being preferably formed of metal. The dispensing cup consists of the lower annular portion 11 which is connected to the top 12 by 95 means of three or more ribs 13, said ribs being flared outwardly at their upper extremities as at 14 for the purpose of retaining the cup within the neck 9, the flared portion 14 engaging the upper inner wall of the neck 9, preventing the cup from dropping through said neck. A plate 15 provided with an annular peripheral, downwardly, disposed flange 16 and a centrally

located elongated sleeve 17 is connected to the top 12 of the dispensing cup by means of a screw or its equivalent 18. Resting upon the top 12 of the dispensing cup is a plurality of segmental covers 19, each of which is provided around its outer edge with a downwardly depending flange 20 and at its inner extremity with an enlarged head 21 adapted to fit between the flange 16 and the sleeve 17, said head having its inner face beveled at 22 in order to allow the cover to be raised as best illustrated in Fig. 4 of the drawings.

Thus it will be seen that a dispensing cup is provided which is open at the bottom and provided with a series of apertures 23 between the ribs 13.

The containing receptacle 1 is filled with oyster crackers or any other suitable and desirable articles adapted to be dispensed therefrom and in order to procure a small quantity of the articles contained therein the user places his hand, palm upward beneath the inverted dispensing cup 10 and raises the cup to the position shown in dotted lines Fig. 1. As the dispensing cup is thus raised it disturbs the crackers or articles contained in the receptacle so that a small number of the crackers will pass through the apertures 23 into the interior of the dispensing cup and will fall into the hand of the operator. The hand, supporting the dispensing cup is then withdrawn with the crackers contained therein and the dispensing cup having its support removed will drop back into its normal position, such as shown in full lines in Fig. 1. The flared portions 14 of the ribs coming into contact with the upper portion of the neck 9 of the containing receptacle will prevent any further downward movement of the cup. It will be noticed that the segmental cover sections 19 may be raised into the position better illustrated in Fig. 4 of the drawings. This construction is for the purpose of preventing any breaking or crumbling of any crackers, which might extend beneath said covers when the dispensing cup is allowed to fall into its normal position.

Although the drawings and above specification disclose the best mode in which I have contemplated embodying my invention I desire to be not limited to the details of such disclosure, for, in the further practical application of my invention, many changes in form and construction may be made, as circumstances require or experience suggests, without departing from the spirit of the invention, within the scope of the appended claims.

I claim:

1. A dispensing device comprising a containing receptacle provided with an aperture in the bottom thereof, an inverted dispensing cup slidably mounted within said

aperture and a hinged cover provided upon the top of said dispensing cup said hinged cover being for the purpose of preventing breaking of any articles contained in said dispensing device which might extend beneath said cover when the dispensing cup drops to its normal position.

2. A dispensing device, comprising a containing receptacle provided with an aperture in the bottom thereof, an inverted dispensing cup slidably mounted within said aperture and a plurality of hinged covers provided upon the top of said dispensing cup.

3. A dispensing device comprising a containing receptacle provided with an inclined bottom having an aperture located in the lowest point thereof, a downwardly disposed neck located around said aperture, an inverted dispensing cup slidably mounted within said neck, said cup provided with apertures, vertical ribs provided around the side wall of said cup, said ribs being outwardly flared at their upper extremities and a plurality of hinged segmental covers provided upon the top of said cup, said hinged segmental covers being for the purpose of preventing breaking of any of the articles contained in said dispensing device which might extend beneath said covers when the dispensing cup drops to its normal position.

4. A dispensing device comprising a containing receptacle provided with an inclined bottom having an aperture located in the lowest point thereof, a downwardly disposed neck located around said aperture, an inverted dispensing cup slidably mounted within said neck, said cup provided with apertures, vertical ribs provided around the side wall of said cup, said ribs being outwardly flared at their upper extremities and a plurality of hinged segmental covers provided upon the top of said cup, each of said segmental covers provided with a downwardly disposed flange around its outer edge, said hinged segmental covers being for the purpose of preventing breaking of any of the articles contained in said dispensing device which might extend beneath said covers when the dispensing cup drops to its normal position.

5. A dispensing device, comprising a containing receptacle provided with an inclined bottom having an aperture located in the lowest point thereof, an inverted dispensing cup slidably mounted within said aperture, said cup provided with apertures in its side wall, a spaced plate connected at the top of said cup, a downwardly disposed peripheral annular flange provided upon said plate, the lower edge of said flange being spaced from the top of said cup, a series of segmental covers located upon the top of said cup, enlarged heads provided upon the inner ends of said segmental covers, inclined inner faces provided upon said heads, said heads being

located beneath said spaced plate, said hinged segmental covers being for the purpose of preventing breaking of any of the articles contained in said dispensing device which might extend beneath said covers when the dispensing cup drops to its normal position.

In testimony that I claim the above, I have hereunto subscribed my name in the presence of two witnesses.

OTTO KARCHER.
